UNITED STATES PATENT OFFICE

2,541,117

BRUSH ADJUSTMENT FOR SUCTION
CLEANERSCharles H. Sparklin, Chicago, Ill., assignor to
Birtman Electric Company, a corporation of
Illinois

Application June 20, 1944, Serial No. 541,140

1 Claim. (CL 15—368)

1

This invention relates to a brush adjustment for a suction cleaner.

The present device provides a means by which the brush may be adjusted without removing it, by which the ends of the brush are synchronously and simultaneously adjusted, and in addition to which, if desired, the position of the bristles may be precisely gauged.

The invention is illustrated in the drawings in which Figure 1 is a plan view of the front portion of the cleaner looking upward; Figure 2 is a sectional elevation thereof taken along the line 2—2 in Figure 1; Figure 3 is a detailed view of one of the brush mounting brackets; Figure 4 is a sectional elevation taken along the line 4—4 in Fig. 1 illustrating the brush in position for attachment of the belt; and Figure 5 is a detailed view taken along the line 5—5 in Figure 2, with the position of the cleaner inverted, illustrating the operation of the gauge.

The invention relates to any conventional type of motor brush cleaner having a casing 10, a motor 11, a fan 12, a belt-driving spindle 13, a power belt 14, and a suction opening 15 leading to a nozzle chamber 16. A brush 20 is mounted in the motor chamber and may be of any conventional type, but the present invention is primarily applicable to one having a series of bristles 21. The bearings 22 for the brush roller are each mounted in a bracket 23. This bracket is pivotally mounted at 24 in the end wall 25 of the nozzle chamber. It is normally urged into engagement with the cam 26 by any suitable means such as a spring 27. When it is in operating position, the cam is engaged by the cam follower surface 28 on the upper side of the bracket. The pivot for the bracket is near the bottom of the nozzle chamber and somewhat in advance of the rear wall 29 thereof. As a result, the brush may be shifted into the position shown in Figure 4 in which the upper edge 30 of the bracket engages the wall 29. At this point the bracket has passed the dead center of the spring so that the brush is held in the position shown in Figure 4. In this position the belt may readily be mounted on the spindle 13 and is held thereon by the collar 31. It will be observed that in this position the brush is considerably closer to the spindle than in its operating position, so that the belt may readily be placed in position. The brush is then retracted to operating position without much effort on the part of the operator.

The position of the brush may then be adjusted by the cams 26. These cams are mounted at the ends of the hexagonal rock bar 40. This bar is encircled by a yoke 41, one arm of which bears a

2

lever arm 42 provided at its end with the gear teeth 43 which engage the worm 44 carried by the adjusting post 45. This post is secured to the casing and is provided at its top with the cap 46 having a rib 47 adapted for easy grasping. Turning of the post 45 raises or lowers, depending upon the direction of turning, the arm 42, and, therefore, rotates the bar 40. Rotation of the bar, which is of course rigid, raises or lowers the cams 26, thereby synchronously adjusting both ends of the brush by movement of the brackets 23.

The appropriate position of the brush may be indicated by the gauge 50 which is pivotally mounted in a bracket 52 secured to the rear wall 15 29 of the nozzle chamber. In its retracted position, as shown in Figure 1, the gauge is immediately outside of the air conduit and does not interfere with operation of the device. When 20 swung into forward position, as shown in Figure 5, the front end 54 of the bracket abuts on the front lip 55 of the nozzle, thereby accurately positioning the registration portion 56 of the gauge. This portion is preferably cut away in a circular segment so positioned that the bottom of the segment indicates precisely the point where the end of the bristles 21 should be, namely, $\frac{1}{8}$ inch below the nozzle lips. The adjusting knob is then turned until the brush is at this point, after which the gauge is returned to its inoperative position.

It is preferred to employ the invention in combination with a belt guard 60 of any suitable type, for example, as described in the copending application of Charles H. Sparklin, Serial No. 539,331 filed June 8, 1944, now abandoned.

The foregoing detailed description has been given for clearness of understanding only, and no unnecessary limitations should be understood therefrom.

40 What I claim as new, and desire to secure by Letters Patent, is:

In a suction cleaner having a nozzle with means forming a nozzle chamber, said nozzle chamber having a nozzle opening in the bottom thereof, a brush rotatable about a substantially horizontal axis in the nozzle chamber, and drive means for rotating said brush, a bracket at each end of the nozzle chamber pivotally mounted at a point adjacent the bottom of the nozzle chamber and supporting the brush for rotation about said axis spaced from the pivot points of said brackets, a bar rotatably mounted about its longitudinal axis located within the nozzle chamber and above said brackets, said bar being arranged substantially parallel to the said axis of rotation of the brush,

cam members mounted on the bar and rotatable therewith, each of said cam members normally bearing against a top portion of one of said brackets, means normally urging said brackets against said cam members, and means for rotating said bar and cam members to rotate the brackets and adjust the position of the brush relative to said nozzle opening, said means for rotating including a member operably connected to the bar and accessible from outside said nozzle chamber.
